Term of patent 14 years

(Cl. D62—2)

FIG. 1

FIG. 2

FIG. 3

FIG. 4

FIG. 5

FIG. 6

FIG. 1 is a perspective view of a stud welding gun or similar article showing the new design;

FIG. 2 is a front elevational view thereof;

FIG. 3 is a rear elevational view thereof;

FIG. 4 is a side elevational view thereof;

FIG. 5 is a top plan view thereof; and

FIG. 6 is a bottom plan view thereof.

The other side of the stud welding gun of the invention is essentially the same as the side shown in FIG. 4 and is therefore not illustrated in the drawings.

The dominant features of the design reside in the portions shown in full lines.

I claim:

The ornamental design for the stud welding gun or similar article, substantially as shown and described.
